TORCHERE FIXTURE

Leslie J. Poglein, Jeannette, Pa., assignor to J. H. Millstein Company, Jeannette, Pa.

Application November 23, 1951, Serial No. 257,817

1 Claim. (Cl. 248—128)

This invention relates to lighting devices and has special reference to a torchere.

In the method now generally used for manufacturing devices of this character, there is provided a relatively shallow bowl from the center of which depends a neck or hub integral with the bowl. In these devices the material used is of translucent character such as glass or other like materials. Due to the peculiar shape of the device the heat from the lamp used in connection with such lighting arrangement causes unequal expansion of the body of the bowl and the neck. Consequently, fractures due to this unequal expansion frequently take place at the junction of the neck and bowl.

One principal object of the present invention is to provide a novel construction of torchere having a shallow bowl-like body and a metallic neck or hub depending from and carried by the body. In this construction, the bowl is, of course, of translucent material.

In the joining of a metal hub to the body the question of unequal expansion again arises. Another important object of the invention is to provide novel means for so connecting the metal hub with a bowl of glass or the like in such manner that while the connection will be firm, compensation is had for the unequal expansion of the glass and metal.

A further object of the invention is to provide a connection between the hub and bowl of such a device whereby the hub may be made of tubular form and without the necessity of providing threaded means for attaching the hub and bowl together.

A still further object of the invention is to provide a novel hub and bowl connection wherein a snap ring is utilized to produce a firm connection while at the same time permitting unequal expansion of the bowl and hub without danger of fracturing the bowl.

With the above and other objects in view that will become apparent as the nature of the invention is better understood, the same consists in general of certain novel details of construction and combinations of parts hereinafter fully described, illustrated in the accompanying drawing and particularly claimed.

In the accompanying drawing, like characters of reference indicate like parts in the several views and in which:

Fig. 1 is a side elevation of a torchere constructed in accordance with this invention,

Fig. 2 is a fragmentary diametric section taken through the device, and

Fig. 3 is a section from line 3—3 of Fig. 2.

In the invention shown in the accompanying drawing, there is provided a shallow bowl 10, which is made of glass or other suitable translucent material. Bowl 10 is

2

provided centrally of its bottom with a circular opening 11. The metal hub which carries the bowl 10 has a lower end 12 of frusto-conical form which flares outwardly adjacent its upper end as shown at 13. This stem or hub is made of thin metal of uniform thickness throughout and at the upper extremity of the flared portion the metal is extended inwardly as at 14 and vertically upward as at 15 to form a cylindrical portion. At the upper edge of the cylindrical portion 15 the metal is extended outwardly as 16 and again upwardly as at 17. The arrangement of the metal at the parts 14, 15, and 16 produces an external groove in the hub. At the upper end of the part 17 the metal is flared outwardly as at 18 to fit on the inside of the bowl 10 around the hole or opening 11 and it is to be noted that a slight spacing exists between the periphery of the hole 11 and the upwardly extending wall portion 17 of the hub, this spacing being indicated at 19. In connection with the neck or hub, there is provided a washer 20, which fits on the outer side of the bowl around the opening 11. This washer is aligned with the hub portion 16. A split ring 21 is seated in the groove of the metal hub and it will be observed, from Fig. 2, that this split ring engages against the inner periphery of the washer 20 so that the washer may expand slightly when heated without becoming detached from its support of the bowl. It will further be noted that by means of this construction the flange 18 is integral with the body of the hub and that there is not required any screw threading in the connection between the hub and the bowl body.

As clearly shown, spring fingers 22 are formed in the lower part of the hub and extend upwardly and inwardly so that the hub may be fitted on the upper end of a lamp standard.

It is obvious that minor changes may be made in the form and construction of this invention without departing from the material principles thereof. It is not therefore desired to confine the invention to the exact form here shown and described but it is desired to include all those forms which may come within the scope of the invention as claimed.

Having thus described the invention, what is claimed as new and desired to be secured by Letters Patent, is:

In a torchere, a bowl body having a centrally disposed opening in its bottom, and a tubular sheet metal hub detachably secured thereto, said hub adjacent its upper end being first bent inwardly and then vertically and then outwardly to provide an annular groove at the outer side of the hub, an upward extension above said groove within the bowl opening and spaced from the edge thereof and an outward extension at the upper terminal end of the hub overlying the upper surface of the bowl adjacent the opening therein, a washer at the underside of the bowl aligned with the outward extension that forms the top wall of the annular groove and a snap ring in said groove for holding the washer engaged with said bowl and the bowl and hub assembled.
